UNITED STATES PATENT OFFICE

2,558,424

BARN CLEANER

Carl F. Dretzke, Manawa, Wis.

Application March 12, 1948, Serial No. 14,569

2 Claims. (Cl. 198—108)

1

This invention relates to an improved barn cleaner and has for its primary object to quickly and readily clean the drainage gutters usual in the floors of barns.

An important object of the invention is to provide an improved chain guide for the chains of the conveyor as it is withdrawn from the barn as it is being cleaned for deposit of manure into a waste receptacle.

A further important object of the invention is to employ an improved type of control whereby a single motor and appropriate connections enable the operator to wind up either the chain cleaners or to wind up the return cable.

A further object of the invention is to provide novel means to connect the cleaner to the barn structure to remain stationary while in use.

A still further object of the invention is to provide an improved chain-return support and guide structure.

And a still further object of the invention is to provide improved chain and cleaning means construction.

And yet another object of the invention is to provide an improved barn door construction especially adapted for the chain cleaners.

Features of the invention provide an especially efficient chain guide construction to prevent the chain links from catching or lifting out of operating position; resilient means to allow for large obstructions while the cleaner is in operation; a double clutch means to selectively wind the chain conveyor or to return it to original position in the barn; lever means to lock the cleaner to the barn structure while the device is to be used; a telescoping standard to guide and center the chain return means; a novel chain and cleaning bar connection; and a slidable barn trap door construction with especial provision to accommodate the cleaner chains while keeping the barn door closed when the device is not in use.

With these and other objects in view, the invention consists in the novel construction, arrangement and formation of parts, as will be hereinafter more specifically described, claimed and illustrated in the drawings, in which:

Figure 1 is a side elevational view of the device of the invention in operating relation with a barn;

Figure 2 is a top plan view of the invention illustrated in Figure 1;

Figure 3 is a rear end elevation of the invention;

Figure 4 is a transverse vertical view of the cleaner and chain guide means;

2

Figure 5 is an enlarged vertical section of the chain return guide and mounting means;

Figure 6 is an enlarged rear view, partly in section, illustrating the clutch control means;

Figure 7 is a plan view of the chain and cleaning bar illustrating the improved connecting means;

Figure 8 is a fractional end view of the cleaner construction of Figure 7;

10 Figure 9 is a front elevational view of the support means for the return cable;

Figure 10 is a front elevational view of the cable guide means within the barn and is taken along the lines 10—10 of Figure 5;

15 Figure 11 is a view similar to Figure 10, but at right angles thereto;

Figure 12 is a front elevation of the barn trap door construction; and

20 Figure 13 is a transverse section taken substantially on lines 13—13 of Figure 12.

This invention represents an improvement over the barn cleaner construction of pending application No. 652,538, filed March 7, 1946 and now forfeited.

25 Referring to the figures, and especially to Figures 1 and 5, 20 designates a barn including a front wall 22, rear wall 24 and floor 26, together with a channeled gutter 28 in which a train of cleaning chains 30 travels.

30 The barn cleaning structure is generally indicated at 32 and includes an inclined trough 34, chain operating member 36 and disk chain guiding wheels 38 supported on horizontal frame member 40 carrying suitable wheels 42 mounted in any desired manner to frame 40 at 44 and riding on tracks 46 as is described in greater detail in copending application, Ser. No. 652,538.

35 Trough 34 consists of a relatively short horizontal leg 48 which is so constructed that it is moved into alignment with channel member 28 for a purpose presently to be described. The inclined section 50 of trough assembly 34 extends upwardly for a considerable length to terminate in an arcuate, grooved end 52, receiving in close proximity thereto a roller 54 over which chains 30 travel to be wound upon a large drum 56.

40 Roller 54 is mounted on transverse shaft 58 rotatably received in bearings 60 secured in any suitable manner, such as by bolts 62, to a pair of braces 64 riveted at 66 to trough 50. A pair of strengthening braces 68 are fastened to braces 64 at one end and to standard support 166 of barn cleaner 10 at the opposite extremity thereof. Trough 34 includes a movable lever 70

pivoted at 71 for connection with the barn structure, as will shortly be explained.

Referring to Figures 1, 2 and 4 particularly, disk guide 38 consists of a pair of parallel disks 72, mounted on a transverse roller 74 a short distance inwardly from the ends thereof and includes a plurality of triangularly shaped guiding members or spades 76 for control of chains 30 which must travel thereunder after they have left barn 20 and prior to travel up inclined trough 50 to the point of disposal below roller 54. This construction is of particular advantage over the usual star or spoke type of guiding wheel used prior to this invention. The individual spoke members of star wheels are very flexible, thus causing them to bend and laterally slip out of position when encountering a particularly large mass of manure carried from a barn by the usual chains, causing some of the refuse to fall over the sides of the trough, or lose control of the chain member, causing them to be raised and spilling their contents. Disks 72 provide the necessary rigidity for chain guide members 76. Flat edges 78 of spades 76 will not catch and detain links, as frequently occurs in the use of forked star wheels, and permit disk 72 to be mounted closer to the base of horizontal leg 48. It is of extreme importance to maintain chains 30 adjacent to leg 48, as otherwise chains 30 might rise and permit some of the removed refuse from the barn to fall through the chains, to be carried back to the barn on the return travel thereof. The diameter of roller 74 assists in preventing spilling of the manure, since it retains the return cable 218 close to leg 48 in the initial movement of the cleaners. In the star wheel type, cable 218 would lift and so raise chains 30 to cause them to drop the waste being removed from the barn. It is to be noted that triangular guides 76 are set at an angle so that they will not lift the manure out of the trough. Thus, roller 74 and disks 72 combine to form a drum structure.

Roller 74 is mounted for rotation on transverse shaft 80 and is received in bearings 82 secured to transverse bars 84 by means of bolts 86, which bearings, in turn, are secured by bolts 88 to two pairs of parallel, resiliently mounted standards 90. Standards 90 include an upper sleeve member 92 telescopically receiving a lower sleeve member 94 riveted at 96 to angle irons 98 welded to the sides of horizontal legs 48 of trough 34. Springs 100 are secured in telescoping sleeves 92 and 94 and are entirely enclosed. Thus, they are protected from the elements and are not subject to mechanical failure due to rusting or freezing, which would occur were they permitted to remain exposed. Springs 100 provide resilient action for guiding wheels 38 and are tensioned in any desired manner, as by means of threaded bolts 102 secured to springs 100 (not shown). Of course, it is to be understood that sleeves 92 could be eliminated and sleeves 94 be extended to connect directly to pipe cap 93. Springs 100 would be placed within pipe 92 and secured to cap 93. The bearing means for rotating disks 72 and roller 74 insure smooth performance, whereas the forked shafts on the usual star wheels are mounted directly on the shaft itself and tend to frictionally bias the structure. In the present construction, should a particularly large mass of manure travel under roller 74, springs 100 would permit members 92 and 94 carrying shaft 80 to temporarily adjust themselves and enable the manure to

pass therethrough. A steel guide 104 is mounted on each side of disk 72 to additionally guard against the manure spilling out of trough 34.

The chain operating means 36, as is best illustrated in Figures 1 to 3 and 6, includes a large chain winding drum 56 mounted on lay shaft 106 received in a bearing 108 and mounted in a housing 110. A large gear 112 is mounted on shaft 106 and engages a smaller gear 114 mounted on drive shaft 116 by means of clutch engaging member 118. Drive shaft 116 has mounted thereon a driven sprocket 120 carried by means of sprocket chains 122 around a sprocket drive member (not shown), being rotated by the take-off power shaft 124 on motor 126. Motor 126 carries a gear reduction means 130 coupled together at 132. The sprocket assembly is enclosed in a housing 134 mounted on brackets 136 bolted at 138 to frame 40 and to chain drum housing 110 at 140. A guard 141 is secured to trough 50 and horizontal frame 40 to protect motor 126 and gear reduction means 130 from being dirtied by manure cleaned from the barn.

25 A lever 142 is pivotally mounted at 144 to flange 146 secured to housing 110 and includes a double-dogged clutch member 148 slidably engageable with either drum means 56 or a cable winding smaller drum 150 rotatably mounted on main shaft 116. Shaft 116 terminates in bearings 152 bolted at 154 to a short channel standard 156 bolted at 158 by means of a short angle bracket to frame 40. Thus, by simply moving lever 142 to the left or to the right, the chain winding drum 56 or the cable winding drum 150 is selectively actuated. An eye member 162 is mounted on drum 150 to receive the end of a cable 218. A brake member 164 including a brake cap and spring therein (not shown) is mounted on one of a pair of supporting standards 166 and engages chain drum 56. Handle 168 is pivotally mounted at 170 to actuate brake rod 172 and is pivotally secured at 174 to flange 176 bolted at 178 to housing 110. Thus, when it is necessary to prevent chain drum 56 from unwinding too rapidly when returning chain 30 to gutter 28, brake 164 is applied by the operator. A switch box 180, of conventional construction, is secured to standards 166 and is connected by means of pipe sleeve 182 with an electric wire 184 leading to barn 20 through 186 to a suitable source of current supply.

55 Barn 20 includes a trap door 188 slidably mounted in oppositely disposed channel members 190 (see Fig. 2). Channel members 190 are of L-shaped construction and include vertical legs 192 and lateral legs 194. Secured to legs 192 are brackets 196 bolted at 198. Legs 194 carry angle arms 200, permitting lever 70 on horizontal leg 48 to lock in place and thereby align gutter 28 with trough 34. Guiding brackets 196 retain door 188 in position and aperture 204 permits the door to be readily raised. A pair of apertures 206 at the base of door 188 allow for chains 30, otherwise trap door 188 could not close tightly. Thus, it is readily apparent that in this type of construction, the entire barn door need not be open in order to clean out the gutter, but it only becomes necessary to raise trap door 188 while the 60 cleaning process is carried out. When the device has been disconnected, trap door 188 is returned to the original position, and again becomes tightly closed. Obviously, this construction is of material importance during the cold weather, as the 65 opening of the barn 20 is reduced to a minimum.

Chains 30 consist of a train of parallel, spaced link members lying in gutter 28 and extend slightly beyond wall 22 of barn 20. Chain 30 continues as a double lead chain 330 beyond the ends of the first of cleats 210 lying in gutter 28, and is wound around drum 56. Channel iron cleats 210 are transversely disposed (see Figs. 7 and 8) and are secured to horizontally disposed link members 29 of chain 30 at predetermined intervals. In this construction, bolts 212 secure cleats 210 by means of lock nuts 214 and washers 216. Bolts 212 are flush with the upper edge of adjacent, vertically positioned link members 31 of chain 30. Thus, injury to the animals and wear on the bolt head is avoided.

Chains 30 terminate at the inner ends in barn 20 and are secured to a cable 218 of either chains or rope, as may be desired, which lead over pulley 220, mounted on transverse pins 222 secured in brackets 224 mounted on a pair of telescoping standards 226, and pulley 228 rotatably mounted on door 22 and leading to drum 150. Standards 226 are telescopically received in standard sleeves 227 and are retained in adjusted position by means of set screws 230. A guide plate 232 is welded between standards 227 and includes chain guide 234 bracketed to the upper edge of plates 232 in axial alignment with pulley 228. A pair of oppositely disposed flanges 236 are secured to standards 227 adjacent the floor 26 of barn 20 and receive a guide roller 238 under which chains 30 travel. Standards 227 are cemented into the barn floor and will not move. The telescoping construction permits installation in any barn, and cable 218 is always in proper alignment whether winding or unreeling.

As is clearly shown in Figures 10 and 11, cable 218 is maintained in aligned position on the ceiling of the barn by means of a U-shaped bar 240 welded to a rod 242 secured to the barn roof by means of lag screws 244. Cable 218 is thus able to move in any direction without danger of catching or snagging.

From the above description, the operation of the device is readily apparent. When it is desired to clean a particular barn, the cleaning device 32 is rolled up before barn door 22 on rails 46, and when in alignment therewith, lever 70 is pivoted into locking position on angle arms 200. Trap door 188 is then raised and chain assembly 36 is ready to be actuated. Motor 126 is then started and will rotate main shaft 116 in idling position by means of the chain and sprocket construction mounted thereon. When the manure in the barn is to be removed, lever 142 is shifted for clutch 148 to engage member 118 to rotate small gear 114, which in turn actuates large gear 112, gear 112, in turn, rotating lay shaft 106 on which chain drum 56 is mounted. Chains 30, in their upward travel on inclined trough assembly 34, must first pass beneath disks 72 and are kept in line by means of spade guides 76. Resilient springs 100 mounted on each side of roller 74 permit temporary displacement of the roller to accommodate unusually large masses of refuse. The material to be disposed is carried by cleats 210 upwardly through inclined leg portions 50 to be discarded over roller 54 at the upper, outer extremity thereof into a disposal receptacle placed below (not shown). Chain 330, meanwhile, is wound up on drum 56. Lead chains 330 are secured to each extremity of drum 56, as shown in Figure 3, and wind up thereon from the outer edges of toward the center of drum 56. The length is such that when chains 330

reach the center of the drum, the first cleat 210 reaches drum 56 and again divides chains 330. While the manure is being removed from the barn, cable 218 is rotated through the action of the chains to unwind in order to compensate for the travel of chains 30. Cable 218 is guided in its path of travel through roller 228 and U-shaped eye members 240 and around pulley 220 which is in vertical alignment with a guide member 234 mounted between parallel telescoping standards 226 and 227 on a plate 232. After the barn has been cleaned, lever 142 is actuated in the reverse direction for clutch 148 to engage cable drum 150 to reverse the direction of travel. This causes cable 218 to wind on drum 150 and correspondingly, chains 330 and 30 are unwound from drum 56. When chains 30 are returned to their original position, trap door 188 is again placed in position and the device is ready to be used with another barn.

While this specification sets forth in detail the present and preferred construction of the device, it is to be understood that deviations may be resorted to as do not form a departure from the spirit of the invention, as defined by the appended claims.

Having described the invention, what is claimed as new is:

1. A barn cleaner comprising a trough, material conveying chains disposed in said trough, a chain operating member connected to one end of said conveying chains, a pair of oppositely disposed disks disposed above said chains, a rotatable shaft extending through said disks, resilient means secured to the extremities of said shaft yieldingly supporting said disks over said chains to guide said chains, said resilient means including an upper sleeve member secured to said shaft concentric with and slidably embracing a concentric lower sleeve member, said lower sleeve being secured to said trough, a cap secured to said upper sleeve member, and a tension spring secured within said sleeves.

2. A barn cleaner comprising a trough, material conveying chains disposed in said trough, a chain operating member attached to one end of said material conveying chains, a chain guide member mounted above said trough and said chains, a pair of spaced, oppositely disposed telescoping standards adapted to be secured in a barn, a guide plate secured to said telescoping standards, a chain guide means mounted on said plate, a pulley carried by said standards and positioned above said guide plate and in axial alignment with said chain guide means, and a roller rotatably mounted at the bottom of said standards around which said material conveying chains are guided, an extension of said chains being guided over said pulley and below said roller.

CARL F. DRETSKE.
